UNITED STATES PATENT OFFICE.

WILLIAM FOSTER, OF PHILADELPHIA, PENNSYLVANIA, ASSIGNOR TO PHILIP H. CHASE, OF BALA, PENNSYLVANIA.

LIGHT-SUPPORT.

Application filed January 2, 1923. Serial No. 610,159.

To all whom it may concern:

Be it known that I, WILLIAM FOSTER, a citizen of the United States, and a resident of Philadelphia, Pa., have invented an Improvement in Light-Supports, of which the following is a specification.

This invention relates to supports for street lamps, and with regard to certain more specific features, to a mast-arm and combined strain insulator and notched hanger.

Among the several objects of the invention may be noted the provision of a simple and inexpensive support for street lamps; and the provision of a device of this character that is slight in appearance, rugged in construction, and adapted to withstand severe service conditions. Other objects will be in part obvious and in part pointed out hereinafter.

The invention accordingly consists of the elements and combinations of elements, features of construction, and arrangements of parts which will be exemplified in the structure hereinafter described and the scope of the application of which will be indicated in the following claims.

In the accompanying drawings, in which is shown one of various possible embodiments of the invention,

Fig. 1 is a right side elevation of a preferred embodiment of the invention;

Fig. 2 is a plan of Fig. 1, omitting the street lamp, strain insulator and hanger;

Fig. 3 is a right side elevation of the insulator and hanger, on an enlarged scale;

Fig. 4 is a front elevation of the insulator of Fig. 3;

Fig. 5 is a front elevation of the hanger of Fig. 3;

Fig. 6 is a horizontal section on the line 6—6 of Fig. 5;

Fig. 7 is a left side elevation of the insulator, showing in solid lines the shape of the cap prior to installation, and in dotted lines the shape after installation; and

Fig. 8 is a central vertical section on the line 8—8 of Fig. 7.

Similar reference characters indicate corresponding parts throughout the several views of the drawings.

Referring now more particularly to Figs. 1 and 2 of the accompanying drawings, there is illustrated at 1 a pole to which are bolted

two substantially horizontal pipes 3, 5 and a 55 diagonal brace pipe 7. The word "pipe" is used herein as generic to devices of various cross-section (such as T, I, U, or angle) as well as devices of hollow circular cross-section. The horizontal pipes are preferably 60 held in position by a through-bolt 9. The diagonal pipe is bolted as at 11 to a clevis 13 which in turn is bolted to the pole 1. The three pipes are connected to each other at their outer ends by means of an end 65 pulley bracket 15 in which is mounted a sheave-wheel 17 around which passes a wire rope 19 having secured at its outer end a street lamp illustrated conventionally at 21. Between the rope 19 and lamp 21 an insulating hook 14 may be provided in case the voltage or other conditions of installation should require such insulation. The end pulley bracket may be provided with a hook 70 10 or other means for attaching a safety 75 hanger 12 or other device for relieving the wire rope of the weight of the lamp except when it is being raised or lowered.

Bolted to the pole 1, at a point adjacent the through-bolt 9, is a back pulley bracket 80 23 having therein a sheave-wheel 25 over which passes the wire rope 19 above mentioned. This bracket is preferably so located that the pulley axis is in the same horizontal plane as the axes of the upper 85 pipes 3, 5.

The end pulley bracket is preferably so constructed that the axis of the pulley 17 therein is at the intersection of the axis of the diagonal pipe 7 with the horizontal 90 plane passing through the axes of the upper pipes 3, 5.

Through the end pulley bracket 15 extends a bolt or stud 20, preferably of bronze, which holds the two horizontal pipes 3, 5 95 firmly against the bracket 15 and at the same time acts as a bearing for the pulley 17. Lugs 24 (Figs. 1 and 2) on the bracket 15 align the horizontal pipes 3, 5 and prevent rotation of the bracket with respect 100 thereto.

Owing to the construction of the end pulley bracket 15 and pole clevis 13, the diagonal pipe 7 is of the same length as the horizontal pipes 3, 5. The three pipes are 105 all provided with flattened ends 22 as indicated in Figs. 1 and 2, and are interchangeable. These features reduce the number of

different parts that need to be carried, and thereby add to the usefulness of the invention.

Upon the horizontal pipes there may be 5 mounted brackets 29 for insulators (not shown) to carry the leads (not shown) to the lamp 21, it being understood that sufficient slack is provided in such leads to permit the lamp to be lowered.

10 The wire rope 19 passes downwardly from the back pulley 25 to a suitable strain insulator, which is secured to the pole in order to hold the lamp in raised position.

A preferred construction for this purpose 15 is illustrated in Fig. 1 and on an enlarged scale in Figs. 3 to 8.

Referring now more particularly to Figs. 3 to 6 there is illustrated at 33 a hanger adapted to be bolted to the pole 1 (Fig. 1), 20 apertures 35 being provided for this purpose. The hanger has a vertical slot 37 extending through the greater part of its length. At one or more places such as 39 the slot is enlarged. At a plurality of 25 places such as 41 the slot has an extension to the left or right and thence upwardly, with preferably a ridge or boss 43 opposite each such extension.

The inner or rear portion of the hanger 30 (to the right in Fig. 3) is cut away or hollowed out to the extent indicated by the dotted lines 49 in Fig. 4.

The hanger is adapted to cooperate with a wood strain insulator 53 (Figs. 3 and 4) 35 having at its upper end a cap 55, and at its lower end a cap 57, both preferably of malleable iron.

As indicated in Figs. 3-4 and 7-8, each cap has a socket 59 the outer end of which 40 is initially of larger diameter than the diameter of the respective portion of the insulator against which this end of the socket bears after installation. The initial contour of the sockets is shown in solid lines 45 in Figs. 7 and 8. When the sockets are applied to the wood, they are slid over the respective end portion of the wood, and then the ends of the sockets are squeezed inwardly to the dotted-line position (Figs. 7 and 8), in which position they remain thereafter and thus securely clamp the ends of the wood.

The upper cap 55 has a clamp 61 (Figs. 3 and 4) for the wire rope 19 above described. This clamp comprises a hollow neck 63 through which the rope passes into the enlarged body portion 65. The rope passes around the central boss 56 and emerges at the opening 58. A bolt 60, held in place by a nut 62, clamps a washer 64 tightly against the rope. Ribs 67 on washer 64 and body portion 65 bite into the rope to assist in holding it against movement in the clamp. A projection 68 on 65 the washer extends into the aperture 69

or 70 to keep the washer from rotating. Lugs 72 on the body portion prevent rotation of the nut or bolt (as the case may be) during tightening of the bolt.

The lower cap 57 has an eye 71 adapted to receive a hook (not shown) such as repair-men carry, attached to a suitable rope (not shown) so that when the repair-man inserts the hook into the eye 71 and removes the lower cap from the hanger, he 75 can lower the lamp, the rope permitting him to control the speed of descent of the lamp and to raise the lamp again when he has finished the work upon it.

The lower cap 57 has also a stud 73 comprising a shank 75 and a nose 77.

The stud 73 extends rearwardly when the insulator is in normal position, and the shank thereof passes through the slot in the hanger 33. The nose 77 at such time is entirely behind the material out of which the central aperture 37 is taken. The contour of said aperture and its extensions is such that when the stud is in any of the notches (that is, in the upper end of any extension 41 or in the upper end 81 of the aperture) the insulator is held against accidental removal because the nose 77 is too large to pass through the aperture at any of such normal operating positions of the device. In order to remove the insulator and stud it is necessary to raise or lower it far enough to bring the nose 77 into registry with an enlarged portion (such as 39) of the aperture, whereupon the stud may be pulled outwardly (to the left in Fig. 3), the nose passing through the aperture. When the insulator is to be secured to the hanger the operator brings the nose 77 opposite enlarged portion 39, inserts the nose into the aperture, and then lowers the stud down the central aperture and swings it to right or left, as the case may be, and allows the stud to pass upwardly to the respective operating position, whereupon he removes the hook above described from the eye 71.

By providing a plurality of operating positions for the stud in the hanger, the hanger serves to compensate for variations in the length of the wire rope. This eliminates slack in the rope, thus keeping the wood strain insulator in an approximately vertical position and avoiding swinging in the wind and avoiding an unsightly appearance.

The top cap may be used with other devices for securing the insulator to the hanger, and similarly the lower cap may be used with other devices for securing the wire rope or other suspension device to the insulator.

The insulator and hanger structure may also be used with other types of mast-arm, and the mast-arm may be used with other

devices for insulating the wire rope and securing it to the pole.

In view of the above, it is believed that the various features of this invention will be clear without further elaboration, and it will be seen that with the apparatus herein described, the several objects of the invention are achieved, and other advantageous results attained.

10 I claim:

1. A mast arm comprising three members of equal length, two of said members being approximately parallel and having their inner ends secured to a pole, the third member

15 extending at an angle to the first members, means for securing the third member to the pole at a point forwardly of the securing point of said first members, a bracket, means extending therethrough and securing 20 the outer ends of the first members to the bracket, and means on said bracket for securing the outer end of the third member thereto at a point rearwardly of the securing point of the first members to said bracket.

25 2. A mast-arm comprising three members adapted to be secured to a pole, one member at an angle to the other two, a bracket, a bolt extending therethrough and adapted to secure the outer ends of said two members 30 to the bracket, a pulley journaled on said bolt, means for securing the outer end of the first member to the bracket, a bracket secured to the pole adjacent said two members, a pulley journaled in said bracket, a 35 rope passing over the pulleys and adapted to carry at its outer end a street lamp; and a hanger therefor adapted to be attached to the pole.

40 3. A mast-arm comprising three members of the same length, two of them approximately horizontal and adapted to be secured to a pole, the third member extending diagonally and adapted to be secured to the pole, a bracket, a bolt extending therethrough and 45 adapted to secure the outer ends of the horizontal members to the bracket, a pulley journaled on said bolt, means for securing the outer end of the diagonal member to the bracket, a bracket secured to the pole adjacent 50 said horizontal members, and a pulley journaled in said bracket, each pulley having its axis substantially in the horizontal plane of the horizontal pipes.

55 4. A mast-arm comprising three pipes of the same length, two of them approximately horizontal and adapted to be secured to a pole by a through-bolt through the pole, the third pipe extending diagonally, means carrying the lower end of the third pipe and adapted to be secured to the pole, a bracket to which are secured the outer ends of the horizontal pipes, a pulley journaled in said bracket, and means for securing the outer 60 end of the diagonal pipe to the bracket.

65 5. A mast-arm comprising three pipes of

the same length, two of them approximately horizontal and adapted to be secured to a pole by a through-bolt through the pole, the third pipe extending diagonally, means carrying the lower end of the third pipe and adapted to be secured to the pole, a bracket to which are secured the outer ends of the horizontal pipes, a pulley journaled in said bracket, means for securing the outer end of the diagonal pipe to the bracket, a 70 bracket secured to the pole adjacent said horizontal pipes, and a pulley journaled in said bracket.

6. A mast-arm comprising three pipes of the same length, two of them approximately horizontal and adapted to be secured to a pole by a through-bolt through the pole, the third pipe extending diagonally, means carrying the lower end of the third pipe and adapted to be secured to the pole, a bracket to which are secured the outer ends of the horizontal pipes, a pulley journaled in said bracket, means for securing the outer end of the diagonal pipe to the bracket, a 75 bracket secured to the pole adjacent said horizontal pipes, a pulley journaled in said bracket, and a rope passing over the pulleys and adapted to carry a street lamp.

7. A mast-arm comprising three pipes of the same length, two of them approximately horizontal and adapted to be secured to a pole by a through-bolt through the pole, the third pipe extending diagonally, means carrying the lower end of the third pipe and adapted to be secured to the pole, a bracket to which are secured the outer ends of the horizontal pipes, a pulley journaled in said bracket, means for securing the outer end of the diagonal pipe to the bracket, a bracket secured to the pole adjacent said horizontal pipes, a pulley journaled in said bracket, each pulley having its axis substantially in the horizontal plane of the horizontal pipes, the axis of the outer pulley passing near or through the axis of the 100 diagonal pipe, and a rope passing over the pulleys and adapted to carry a street lamp.

8. A mast-arm comprising three pipes of the same length, two of them approximately horizontal and adapted to be secured to a pole by a through-bolt through the pole, the third pipe extending diagonally, means carrying the lower end of the third pipe and adapted to be secured to the pole, a bracket to which are secured the outer ends of the horizontal pipes, a pulley journaled in said bracket, means for securing the outer end of the diagonal pipe to the bracket, a bracket secured to the pole adjacent said horizontal pipes, a pulley journaled in said bracket, each pulley having its axis substantially in the horizontal plane of the horizontal pipes, the axis of the outer pulley passing near or through the axis of the 115 diagonal pipe, a rope passing over the pulleys and adapted to carry a street lamp.

pulleys and adapted to carry a street lamp, a hanger for the other end of the rope, and means for attaching the rope thereto.

9. A mast-arm comprising three pipes of the same length, two of them approximately horizontal and adapted to be secured to a pole by a through-bolt through the pole, the third pipe extending diagonally and adapted to be secured to the pole, a bracket, a bolt extending horizontally therethrough and adapted to secure the outer ends of the horizontal pipes to the bracket, a pulley journaled on said bolt, means for securing the outer end of the diagonal pipe to the bracket, a bracket secured to the pole adjacent said horizontal pipes, and a pulley journaled in said bracket, each pulley having its axis substantially in the horizontal plane of the horizontal pipes, the axis of the outer pulley passing near or through the axis of the diagonal pipe.

10. A mast-arm comprising three pipes of the same length, two of them approximately horizontal and adapted to be secured to a pole by a through-bolt through the pole, the third pipe extending diagonally, a clevis carrying the lower end of the third pipe and adapted to be secured to the pole, a bracket, a bolt extending horizontally therethrough and adapted to secure the outer ends of the horizontal pipes to the bracket, a pulley journaled on said bolt, means for securing the outer end of the diagonal pipe to the bracket, a bracket secured to the pole adjacent said horizontal pipes, a pulley journaled in said bracket, each pulley having its axis substantially in the horizontal plane of the horizontal pipes, the axis of the outer pulley passing near or through the axis of the diagonal pipe, a rope passing over the pulleys and adapted

to carry at its outer end a street lamp and at its inner end a strain insulator, and a hanger therefor.

11. A mast-arm comprising three pipes of the same length, two of them approximately horizontal and adapted to be secured to a pole by a through-bolt through the pole, the third pipe extending diagonally, a clevis carrying the lower end of the third pipe and adapted to be secured to the pole, a bracket, a bolt extending horizontally therethrough and adapted to secure the outer ends of the horizontal pipes to the bracket, a pulley journaled on said bolt, means for securing the outer end of the diagonal pipe to the bracket, a bracket secured to the pole adjacent said horizontal pipes, a pulley journaled in said bracket, each pulley having its axis substantially in the horizontal plane of the horizontal pipes, the axis of the outer pulley passing near or through the axis of the diagonal pipe, a rope passing over the pulleys and adapted to carry at its outer end a street lamp and at its inner end a strain insulator, and a hanger therefor, adapted to be attached to the pole and having a portion spaced from the pole and notched at different heights, the upper end of each notch being of reduced diameter, and the strain insulator having a stud comprising a shank and a nose, the shank being of smaller diameter than the upper end of each notch, the nose being of larger diameter than such upper end but of smaller diameter than another portion of the notch.

In testimony whereof, I have signed my name to this specification this 27th day of December, 1922.

WILLIAM FOSTER.
